ARTIFICIAL LEG

Carl L. Freeman, Canton, Ohio, assignor of one-half to Engineering Research Corporation, a corporation of Ohio

Application July 3, 1929. Serial No. 375,650

21 Claims. (Cl. 3—2)

My invention relates to an artificial leg including a thigh member adapted for connection with a leg stump, and a shin member pivotally connected at its upper end at a knee joint with 5 the lower end of the thigh member.

The objects of the present improvements include the provision of novel means for controlling the movement at the knee joint of the shin member with respect to the thigh member in a 10 natural manner, when the person upon whom the leg is applied performs the natural movements of walking by swinging the stump, and without requiring much if any movement of the other parts of the body to operate the artificial 15 leg, as is necessitated in other forms of artificial legs.

These and ancillary objects are attained in the present invention, which will hereinafter be set forth in greater detail, and claimed.

20 A preferred embodiment of the improvements is illustrated in the accompanying drawing forming part hereof, in which

Figure 1 is a side perspective view illustrating an embodiment of the improved artificial leg in 25 use upon a man;

Fig. 2, a perspective view with portions broken away illustrating the improved means controlling the knee action of the leg;

Fig. 3, an end elevation as in the direction of 30 the arrows 3—3, illustrating the control lever for the improved leg, detached from the leg; and

Fig. 4, a side elevation of a modified embodiment of the control lever.

Similar numerals refer to similar parts 35 throughout the several views.

The improved artificial leg indicated generally at 10, includes a thigh member, preferably in the form of a thigh shell 11, and a shin or shank member, preferably in the form of a shin shell 12, and the lower end of the thigh shell 40 is pivotally connected with the upper end of the shin shell by a knee bolt 13.

The front lower knee end 14 of the thigh shell, curves to the rear and fits between side 45 wings 15 formed at the upper end of the shin shell, and the knee bolt 13 extends through suitable registered apertures in the wings 15 and the lower end of the thigh shell.

An improved control lever indicated generally 50 at 17 is pivotally mounted on the knee bolt 13, within the hollow thigh member, and parts of the control lever extend to the rear and downwardly into the hollow shin member through a vertical slot 18 formed at the rear in the lower end of 55 the wall 19 of the thigh shell 11. The knee bolt

13 passes through a bearing aperture 20 formed in the control lever.

The control lever 17 preferably includes a lower arm 21 below the knee bolt, and an upper arm 22 above the knee bolt; and the lever may be 60 formed by side members 23a and 23b, formed of sheet metal, and between the lower arm portions of which may be interposed a spacer block 24 which may be made of wood, and the side members may be secured to the spacer block 65 as by means of rivets 25.

The lower arm 21 of the control lever depends 70 through the slot 18 into the interior of the shin shell 12, and is secured to the shell 12 as by means of a sleeve 26 which may be formed by 75 a U strap 27, the outer ends of which are secured to the interior of the shin shell.

The arm 21 is preferably curved from the knee bolt downwardly, as illustrated; and a resilient pad 28 of felt or the like, is secured to the shin shell and is interposed between the interior surface of the shell and the rear surface 29 of the 80 curved lower arm 21.

The upper arm 22 of the control lever includes 85 a forwardly and upwardly extending inner leg 30, from the upper end of which an intermediate leg 31 extends rearwardly, and an outer leg 32 extends downwardly from the outer end of the intermediate leg 31.

In other words, the upper arm 22 is in the form 90 of a hook extending from the forward side of the knee bolt upwardly, rearwardly and downwardly so that an upward force applied at the outer end of the arm 22 applies a downward force 95 at the upper end of the relatively short inner leg 30 tending to rotate the whole control lever about the knee bolt.

The upper arm of the control lever is preferably 95 formed only by the side members 23a and 23b, which preferably include at their outer upper ends, bearing brackets 33a and 33b; and a transversely extending cord guide member, preferably a grooved roller 34 is pivotally mounted on a shaft 36a, the ends of which are secured in the bearing brackets 33a and 33b. The roller 34 is thus at 100 the rear of and below the knee bolt 13.

At the junction between the inner leg 30 and the intermediate leg 31, another transversely extending cord guide member, preferably a grooved roller 35 is mounted between the side members 105 on a shaft 36b, the ends of which are secured in the side members 23a and 23b. The roller 35 is thus above and forwardly of the knee bolt 13.

As illustrated, in order to best attain the de- 110

sired operation of the control lever 17, the rear cord guide roller 34 is located at a greater distance than the forward guide roller 35 from the axis of rotation of the control lever 17 which 5 coincides with the axis of the knee bolt 13.

A resilient tension member 37 is connected at its upper end with the thigh member, and at its lower end with the outer end of the control lever arm 22, as by means of a pin 38.

10 Control cords 39 are connected at their rear end with the rear end of a harness 40 carried on the shoulders of the person 41 upon which the leg is fitted by insertion of the thigh stump 42 into the upper open end of the artificial leg thigh 15 shell 11.

The cords 39 extend from their rear end connection with the harness downwardly through a guide loop 43 on the rear of the thigh member, thence to the rear of and under the roller guide 20 member 34, thence over the top of the knee bolt 13 between the lever side members 23a and 23b, thence beneath the roller guide member 35, thence through an aperture 44 in the front of the thigh shell wall 19, and thence upwardly to 25 a connection with the front end of the harness 40.

It is to be noted that each of the roller guide members 34 and 35 are mounted directly on the control lever, so that a force applied on either of the guide members applies a torque to the 30 lever, the torques thus applied being opposite to each other.

The modified embodiment 17' of the control lever illustrated in Fig. 4 is similar to the control lever 17, with respect to the location of the 35 rollers, but in the modified control lever 17', the upper arm 22' is not hook shaped and its connection with the roller arm is midway between the rollers, instead of at the end of a hook.

The operation of the improved artificial leg 40 for walking forward, results in movements of the thigh and shin shells or members thereof, which very nearly correspond to the natural movements of a live leg; and the artificial leg is operated primarily by the natural swinging movement of the thigh stump, with little or no exertion by the body and shoulders.

When the thigh stump is raised, the cords 39 lift on the roller 34, thereby causing the roller arm 21 to push backwards against the shin member, and causing the same to move in a natural 50 manner.

The backward rotary movement of the shin member is limited by the forward roller 35 impinging against and taking up the slack in the 55 cord, and the impinging of the forward roller 35 against the cords causes a rebound in the cords which quickly brings the shin member back to a position in substantial alignment with the thigh member, for carrying the weight of the 60 body thereon.

When the weight of the body is carried on the artificial leg, the lower end surface 45 of the slot 18 strikes against the front of the arm 21, causing the lower end of the arm to push against the 65 resilient pad 28.

The resilient tension member 37 acts as a shock absorber for stopping the return movement of the shin shell to the load supporting position.

The net result of the operation of the control 70 lever by the cords, is to start and stop the swinging movement of the shin member in a manner similar to the natural movements of the same.

Too slow or too rapid a swinging of the shin member prevents the user of an artificial leg 75

from walking naturally, and increases the work of operating the leg.

When a person using the improved leg hereof is standing and desires to step backwards with the artificial leg or to kneel on the same, a slight lift of the shoulder kicks the shin backward by a pulling of the cords upwards on the roller 34.

In other legs, raising the shoulder straightens the thigh and shin members with respect to each other.

The hook shape of the arm 22 provides a spring action which eases the strain of operating the leg.

I claim:

1. An artificial leg including a thigh member adapted for connection to a thigh stump, shank member, a knee bolt pivotally connecting the lower end of the thigh member with the upper end of the shank member, a control lever rotatably mounted on the knee bolt, the control lever including an arm depending from the knee bolt and engaging the shank member for rotating the shank member when the arm rotates, a transversely extending cord guide member secured directly on the lever at the rear of the knee bolt 90 and another transversely extending cord guide member secured directly on the lever forwardly of the knee bolt, and a control cord extending from the rear downwardly and under the first guide member, thence over the top of the knee bolt, and thence beneath the other guide member the ends of the control cord being adapted for connection with a shoulder harness.

2. An artificial leg including a thigh member adapted for connection to a thigh stump, a shank member, a knee bolt pivotally connecting the lower end of the thigh member with the upper end of the shank member, a control lever rotatably mounted on the knee bolt, the control lever including an arm depending from the knee bolt and engaging the shank member for rotating the shank member when the arm rotates, a roller cord guide member secured directly on the lever at the rear of the knee bolt and another roller cord guide member secured directly on the lever forwardly of the knee bolt, and a control cord extending from the rear downwardly and under the first guide member, thence over the top of the knee bolt, and thence beneath the other guide member 120 the ends of the control cord being adapted for connection with a shoulder harness.

3. An artificial leg including a thigh member adapted for connection to a thigh stump, a shank member, a knee bolt pivotally connecting the lower end of the thigh member with the upper end of the shank member, a control lever rotatably mounted on the knee bolt, the control lever including an arm depending from the knee bolt and engaging the shank member for rotating the shank member when the arm rotates, a transversely extending cord guide member secured on the lever at the rear of and below the knee bolt and another transversely extending cord guide member secured on the lever above and forwardly of the knee bolt, and a control cord extending from the rear downwardly and under the first guide member, thence over the top of the knee bolt, and thence beneath the other guide member, the ends of the control cord being adapted for connection with a shoulder harness.

4. An artificial leg including a thigh member adapted for connection to a thigh stump, a shank member, a knee bolt pivotally connecting the lower end of the thigh member with the upper 150

knee bolt, and a control cord extending from the rear downwardly and under the first guide member, thence over the top of the knee bolt, and thence beneath the other guide member, 5 the ends of the control cord being adapted for connection with a shoulder harness.

12. An artificial leg including a thigh member adapted for connection to a thigh stump, a shank member, a knee bolt pivotally connecting the 10 lower end of the thigh member with the upper end of the shank member, a control lever rotatably mounted on the knee bolt, the control lever including an arm and a hook, the arm depending from the knee bolt and engaging the shank 15 member for rotating the shank member when the arm rotates, a roller cord guide member secured on the hook at the rear of and below the knee bolt and another roller cord guide member secured on the hook above and forwardly of the 20 knee bolt, and a control cord extending from the rear downwardly and under the first guide member, thence over the top of the knee bolt, and thence beneath the other guide member, the ends of the control cord being adapted for connection with a shoulder harness. 25

13. An artificial leg including a thigh member adapted for connection to a thigh stump, a shank member, a knee bolt pivotally connecting the lower end of the thigh member with the upper 30 end of the shank member, a control lever rotatably mounted on the knee bolt, the control lever including an arm and a hook, the arm depending from the knee bolt and engaging the shank member for rotating the shank member 35 when the arm rotates, a transversely extending cord guide member secured on the hook at the rear of the knee bolt and another transversely extending cord guide member secured on the hook forwardly of the knee bolt, a control cord 40 extending from the rear downwardly and under the first guide member, thence over the top of the knee bolt, and thence beneath the other guide member, the ends of the control cord being adapted for connection with a shoulder harness, 45 and a resilient member connecting the thigh member with the lever at the rear of the knee bolt.

14. An artificial leg including a thigh member adapted for connection to a thigh stump, a shank 50 member, a knee bolt pivotally connecting the lower end of the thigh member with the upper end of the shank member, a control lever rotatably mounted on the knee bolt, the control lever including an arm and a hook, the arm depending 55 from the knee bolt and engaging the shank member for rotating the shank member when the arm rotates, a roller cord guide member secured on the hook at the rear of the knee bolt and another roller cord guide member secured on the hook 60 forwardly of the knee bolt, a control cord extending from the rear downwardly and under the first guide member, thence over the top of the knee bolt, and thence beneath the other guide member, the ends of the control cord being adapted 65 for connection with a shoulder harness, and a resilient member connecting the thigh member with the lever at the rear of the knee bolt.

15. An artificial leg including a thigh member adapted for connection to a thigh stump, a shank 70 member, a knee bolt pivotally connecting the lower end of the thigh member with the upper end of the shank member, a control lever rotatably mounted on the knee bolt, the control lever including an arm and a hook, the arm depending from the knee 75 bolt and engaging the shank member for rotat-

ing the shank member when the arm rotates, a transversely extending cord guide member secured on the hook at the rear of and below the knee bolt and another transversely extending cord guide member secured on the hook above and forwardly of the knee bolt, a control cord extending from the rear downwardly and under the first guide member, thence over the top of the knee bolt, and thence beneath the other guide member, the ends of the control cord being 80 adapted for connection with a shoulder harness, and a resilient member connecting the thigh member with the lever at the rear of the knee bolt.

16. An artificial leg including a thigh member adapted for connection to a thigh stump, a shank member, a knee bolt pivotally connecting the lower end of the thigh member with the upper end of the shank member, a control lever rotatably mounted on the knee bolt, the control lever including an arm and a hook, the arm depending from the knee bolt and engaging the shank member for rotating the shank member when the arm rotates, a roller cord guide member secured on the hook at the rear of and below the knee bolt 90 and another roller cord guide member secured on the hook above and forwardly of the knee bolt, a control cord extending from the rear downwardly and under the first guide member, thence over the top of the knee bolt, and thence beneath the other guide member, the ends of the control cord being adapted for connection with a shoulder harness, and a resilient member connecting the thigh member with the lever at the rear of the knee bolt. 100

17. A control lever for an artificial leg and the like adapted for rotating about an axis, and including portions extending on opposite sides of the axis, and a pair of spaced cord guide members secured directly on the lever at opposite sides of the axis, one of the guide members being normally forward of and above and the other being normally rearward of and below the axis. 115

18. A control lever for an artificial leg and the like adapted for rotating about an axis, and including portions extending on opposite sides of the axis, and a pair of spaced roller cord guide members secured directly on the lever at opposite sides of the axis, one of the roller guide members being normally forward of and above 120 and the other being normally rearward of and below the axis. 125

19. An artificial leg comprising a thigh section, a shin section pivotally connected therewith, a control member mounted on said shin section and 130 having a portion projecting above the pivotal axis and having guide means rigidly mounted on said portion and spaced radially with reference to said axis, one of said means being located forwardly and above said axis when the leg is in 135 normal straightened position, a suspender cord for said leg extending under both guide means and having its intermediate portion between said guide means passing above said pivotal axis, said cord exerting a greater force on said forward guide and a lesser force on said other guide means as said shin section passes to a bent position. 140

20. An artificial leg including a thigh member adapted for connection to a thigh stump, a shank member, means pivotally connecting the lower end of the thigh member with the upper end of the shank member, a control lever mounted for rotation coaxial with the pivotal connecting means and engaging the shank member, the con- 150

trol lever including portions extending on opposite sides of the pivotal connecting means, and spaced cord guide members secured directly on the lever at opposite sides of the pivotal connecting means, the normally forward cord guide member being normally above the axis of the pivotal connecting means and the normally rearward cord guide member being normally below the normally forward cord guide member and 10 the distance of the normally forward cord guide member from the axis of the pivotal connecting means being less than the distance of the normally rearward cord guide member from the axis of the pivotal connecting means, and a control 15 cord operatively associated with the guide members on the lever.

21. A control lever for an artificial leg and the like adapted for rotating about an axis, and including portions extending on opposite sides of the axis, spaced cord guide members secured directly on the lever at opposite sides of the axis, one of the guide members being normally forward of and above the axis, and the other cord guide member being normally rearward of the axis and below the normally forward cord guide member, and the normally rearward cord guide member being spaced radially from the axis a greater distance than the normally forward cord guide member. 80 85
